UNITED STATES PATENT OFFICE.

JAMES DRAYTEN McFARLAND, JR., OF PROSPER, OREGON.

CRANK-HANDLE.

SPECIFICATION forming part of Letters Patent No. 569,346, dated October 13, 1896.

Application filed March 2, 1896. Serial No. 581,596. (No model.)

To all whom it may concern:

Be it known that I, JAMES DRAYTEN McFARLAND, Jr., a citizen of the United States, residing at Prosper, in the county of Coos 5 and State of Oregon, have invented a new and useful Crank-Handle, of which the following is a specification.

My invention relates to improvements in crank-handles that are used to drive logging-jacks or other devices by hand-power; and the objects of my improvement are, first, to reduce the liability to injury of the operator by being struck by the reverse movement of the handle should the holding-ratchet break, 15 or from other causes; second, to provide a handle that will enable a person to get the full benefit of all the leverage in the logging-jack, and, third, to afford facilities for operating the logging-jack in close quarters where 20 a complete revolution of the handle cannot be made. I attain these objects by the mechanism illustrated in the accompanying drawings, in which—

Figure 1 is a longitudinal section of the entire handle; Fig. 2, a perspective view of the cross-head and part of the body of the handle, showing how the cross-head appears with the ratchet removed; Fig. 3, a detailed view in perspective of the ratchet. The section-view 25 is taken on line 1 2, Figs. 2 and 3.

Similar letters refer to similar parts throughout the several views.

The cross-head A, the tube E, and the handhold D constitute what may be termed the 35 "fixed" parts of the handle. The cross-head is shrunk on one end of the tube E. At the other end the handhold D is shrunk on, forming a right angle to the tube and parallel with the hole G in the cross-head. In the hole G 40 is placed the ratchet B, which may be retained in position by the flanges g g, being shrunk onto each end of the ratchet, or it may be threaded for the reception of the flanges.

Through the tube E extends the pawl or 45 dog rod C. This rod is bent at a to conform to the shape of the handhold. It is again bent at b, so as to pass into a hole e in the handhold. This hole is of two sizes, the smaller opening being on the side where the 50 rod enters. The rod is threaded at d for the reception of a nut i. As this nut is in the larger part of hole e it will retain the rod in

its place in the handle. The rod is concaved from a to b on the inner side so as to fit the convex surface of the handhold when the two 55 are pressed together, thereby forming an even surface for the grasp of the hand.

In the ratchet B are a series of holes c c c for the reception of end h of the pawl-rod C. These holes are countersunk or flaring at the 60 end the pawl-rod enters. They extend through the shell of the ratchet into the square hole F, so that any foreign substance that may clog them can be easily removed. The square hole F extends through the ratchet from end 65 to end and is for the reception of the shank or stem of the logging-jack or other machine to which the handle may be applied.

The handle is operated by pressing the handhold and rod together, causing the end h 70 to enter one of the holes in the ratchet, when the ratchet can be turned in either direction. (As all logging-jacks or other devices to which the handle is of any benefit are provided with holding ratchets and pawls I do not deem it 75 necessary to show any part of them.) As the pressure is removed the spring f, which is secured at one end to the handhold, will force the rod out of contact with the ratchet. The load is then held by the holding-ratchet above 80 mentioned, while a new hold is being secured with the handle. Should the holding-ratchet break or the screw slip, the handle-ratchet can turn freely in the cross-head while the handle remains motionless. This handle may 85 be made with the ratchet-holes in the shank or stem of the device to be driven. I prefer it as herein shown and described, as it will, I think, prove more serviceable. The handle may also be made with two parallel rods, one 90 of which will form the body of the handle and be shrunk in the cross-head, the other to be the pawl or dog rod and to slide in a slot on the cross-head, the two to be bent to form a handhold and in all other respects to be as 95 the style described. I prefer the handle as shown, as it is more compact.

Therefore, what I claim as my invention, and desire to secure by Letters Patent, is—

1. A crank-handle consisting of a hollow 100 shank, an eye in the end of said shank, a bushing with a square hole, and a series of holes around the circumference thereof, a locking-rod passing through the hollow of the

shank and adapted to enter the circumferential holes in the bushing, and a spring for normally holding said rod out of engagement with said holes, all substantially as described.

5. 2. The combination of a crank-handle, with a locking-rod adapted to enter circumferential holes, or slots, on the stem of the device to be operated, and a spring for normally

holding said rod out of engagement with said holes, or slots, all substantially as described, for the purposes specified.

JAS. DRAYTON MCFARLAND, JR.
